FOLLOWER FOR FILING COMPARTMENTS

Hans W. Regenhardt, Cleveland, Ohio, assignor
to Record Files, Inc., Wooster, Ohio, a corporation of Ohio

Application June 29, 1945, Serial No. 602,286

9 Claims. (Cl. 129—27)

1

This invention relates to followers for filing compartments and the like and more particularly to adjustable followers adapted to support the cards or other material contained in the compartments or drawers of filing cabinets.

A general object of the present invention is the provision of an improved assembly of follower and locking device therefor, for filing compartments, which can be locked firmly in any desired position and which can be readily released and moved to another position of adjustment. Another object is the provision of such a follower assembly which can be manufactured economically. Another object is the provision of an assembly of follower and locking device wherein the locking device not only holds the follower against horizontal movement due to the pressure of the cards or other material in the file, but also braces the follower against bending by the pressure of the material, and further prevents the follower from falling forward when the pressure of the material is released. A further object is to provide a follower and locking assembly which can be easily installed in a filing compartment. Another object is the provision of such a device made up of only two simple parts which can be manufactured economically from sheet metal.

Further objects and advantages of my invention will become apparent from the following description of a preferred form thereof. The essential characteristics are summarized in the claims.

Referring to the drawings, Figure 1 illustrates a follower block assembly embodying my invention installed in a compartment such as a drawer of a card file, parts of the compartment being broken away for convenience in illustration; Figure 2 is a rear elevational view showing the assembly of Figure 1, the view being taken as indicated by the line 2—2 of Figure 1; Figure 3 is a transverse sectional view illustrating the locking engagement of the parts with the compartment and taken along line 3—3 of Figure 2; and Figure 4 is a perspective view of the locking device removed from the compartment.

The device is shown as installed in a filing compartment indicated in general at 10 and of more or less conventional construction. The compartment comprises a bottom portion 11, side walls 12 and conventional front and back end members which are not shown in the drawings. The upper edges of the side walls 12 are flanged inwardly as at 14, then downwardly as at 15 providing inverted channels 16 extending

2

along the upper edges of the side portions 12. This construction gives added strength and stiffness to the side portions, and as will appear below, the locking device for the follower engages the inwardly extending flanges, i. e., within the channels 16.

The follower itself, indicated in general at 17, is preferably formed of sheet metal and consists merely of a vertical portion 19, flanged as at 20 at its upper edge for stiffness, and a lower horizontally extending base portion 21 which rests on the bottom 11 of the compartment and is arranged to slide thereon. Figures 1 and 2 show the rear side of the follower, the substantially smooth front side being adapted to engage and support the material within the compartment.

In order to lock the follower in any desired position of adjustment and also to support and brace it against the pressure of the cards and prevent it from falling forward when the pressure of the card is released, the locking device indicated in general at 23 is employed. This consists of two end cam or locking members 24, rounded at their ends and preferably somewhat elongated and egg-shaped as shown, the end members being joined together by the transverse portion 25. The end members 24 are dimensioned with respect to the depth of the side walls 12 of the compartments so that they can be rocked into wedging or locking engagement between the base 21 of the follower 17 and the underside of the flanges 14 within the channels 16. It is to be noted that the end members 24 are stepped inwardly as at 26 and 27 with the result that the distance between the lower portions 28 of the members 24 is less than the distance between the top portions 29 thereof. This arrangement permits the top portions 29 to engage within the channels 16 while the bottom portions 28 engage the base portion 21 of the follower. The follower is of less width than the distance between the downwardly extending portions 15 to permit the follower readily to be inserted into and removed from the compartment.

The wedging and locking engagement of one of the end cam members 24 is shown particularly in Figure 3. As there illustrated, the bottom of the rounded lower portion 28 engages the base 21 of the follower at the point indicated by the reference character 30, while, preferably but not necessarily, a forward portion thereof engages the vertical portion 19 of the follower, as indicated at 31. At the same time,

the rounded upper portion 29 of the cam member 24 engages within the channel 16 at the top of the side wall 12 as at 32. It will be noted that the distance between the vertical portion 19 of the follower and the point of engagement 32 is greater than the distance between the same vertical portion 19 and the point of engagement 30. Thus the axis of the cams extends obliquely with respect to the vertical portion, and forces exerted against the follower in the direction of the arrow shown in Figure 3 will tend to wedge the portion 24 more firmly into position between the bottom 21 of the follower and the channel 16. At the same time, the engagement at the point 31 supports the vertical portion 19 against bending or rocking movements (in a clockwise direction in Figure 3), and when the pressure of the cards is released, the engagement at the point 30 will prevent the follower block from falling forward (counterclockwise or to the left in Figure 3).

The follower and locking device assembly can be manipulated readily. Thus the follower can be locked in its desired position merely by rocking the upper part of the locking device toward the follower until the upper end portions 29 are wedged in position; the lower portions rolling or sliding with respect to the base and the vertical portion until the upper portion is firmly in engagement with the flanges. For convenience in carrying out this operation and also to strengthen the locking device, the transverse portion 25 is preferably flanged or beaded as at 33, the flanged or beaded portion being readily engaged by the fingers of the user. The follower may be unlocked to be moved to another position of adjustment merely by rocking the locking device away from the follower, i. e., in a clockwise direction in the arrangement shown in the drawings. The follower may be installed in the compartment without difficulty because it is narrower than the minimum width of the compartment. The locking device also may be installed easily by positioning it obliquely with respect to the compartment and with the end members 24 with their long axes substantially horizontal, inserting the device into the compartment and adjacent the bottom of the compartment, then moving the device into a position extending across the compartment and adjacent the follower, and finally rotating it into the position such as that shown in the drawings with upper portions 29 of the ends disposed within the channel 16 and the lower portions 28 in engagement with the base portion 21 of the follower.

As noted above, the follower itself is preferably a simple sheet metal part which may be produced by very economical bending operations. The locking device is also preferably formed from sheet metal, and as those skilled in the art will readily appreciate, it may be formed integrally by cutting out the end portions and the transverse portion from a suitable blank, forming the bead or flange 33 on the transverse portion and the steps of the end portions, and bending the end portions into position at right angles to the transverse portion. Thus the device only requires two extremely simple parts which can be manufactured economically and rapidly by simple stamping, bending or forming operations.

From the foregoing description of a preferred form of my invention, it will be evident that I have provided a simple and effective follower assembly for filing cabinets. My assembly can be manufactured from sheet metal at low cost. My

device can be readily adjusted to any desired position, firmly locked in the desired position and locked or released with little difficulty. The pressure exerted by the cards or other material against the follower increases the efficiency of the locking mechanism, yet the follower may be released by simple rotational movement of the locking device. The locking device not only supports the follower against displacement in a rearward direction, but also supports the follower against bending and prevents it from falling forward when the pressure of the cards is released.

Those skilled in the art will appreciate that various changes and modifications may be made in my invention without departing from the spirit and scope thereof. Accordingly, it will be understood that my patent is not limited to the preferred form described herein or in any manner other than by the scope of the appended claims.

I claim:

1. A follower assembly for a filing compartment having a bottom wall and side walls, at least one of said side walls having an inwardly extending flange disposed above the level of the bottom wall, said assembly comprising a follower having an upwardly extending portion adapted to support material within the compartment and a base extending therefrom and adapted to lie along the upper surface of said bottom wall, and means for locking said follower in position within the compartment comprising a member adapted to be wedged between said inwardly extending flange and the upper surface of said base, and having an intermediate portion adapted to engage and support the upwardly extending portion of said follower.

2. A follower assembly for a filing compartment having a bottom wall and side walls, at least one of said side walls having an inwardly extending flange disposed above the level of the bottom wall, said assembly comprising a follower having an upwardly extending portion adapted to support material within the compartment and a base extending therefrom and adapted to lie along the upper surface of said bottom wall, and means for locking said follower in position within the compartment comprising a thin sheet metal cam member disposed in a generally vertical plane and having rounded ends adapted to be rocked into locking position between said inwardly extending flange and the upper surface of said base, the portion of said member engaging said flange being laterally offset from the portion thereof engaging said base.

3. A follower assembly for a filing compartment having a bottom wall and side walls, at least one side wall having inwardly extending flanges disposed above the level of the bottom wall, said assembly comprising a follower having an upwardly extending portion adapted to support material within the compartment and a base portion extending therefrom and adapted to lie along the upper surface of said bottom wall, and means for locking said follower in position within the compartment comprising an elongated cam member having rounded ends adapted to be rocked into locking engagement with said inwardly extending flange and said base portion, and having an intermediate portion adapted to engage and support the upwardly extending portion of said follower.

4. A follower assembly for a filing compartment having a bottom wall and side walls provided with inwardly extending flanges disposed

above the level of the bottom wall, said assembly comprising a follower having an upwardly extending portion adapted to support material within the compartment and a base portion extending therefrom and adapted to lie along the upper surface of said bottom wall, and means for locking said follower in position within the compartment comprising an elongated member adapted to be rocked into locking engagement with said inwardly extending flanges and said base portion, said elongated member having at its ends egg-shaped locking members the radius of curvature of which is least where such locking members engage said inwardly extending flanges.

5. A follower assembly for a filing compartment having a bottom wall and oppositely disposed side walls having inwardly extending flanges disposed above the level of the bottom wall, said assembly comprising a follower having an upwardly extending portion adapted to support material within the compartment in front of the follower and a base extending rearwardly therefrom and adapted to lie along the upper surface of said bottom wall, and a unitary device for locking said follower in position within the compartment comprising a transverse connecting portion having cam members at opposite ends thereof, said cam members being adapted to be rocked into locking engagement with said inwardly extending flanges and said base and having intermediate portions adapted to engage and support the upwardly extending portion of said follower.

6. A follower assembly for a filing compartment having a bottom wall and oppositely disposed side walls having inwardly extending flanges disposed above the level of the bottom wall, said assembly comprising a follower having an upwardly extending portion adapted to support material within the compartment in front of the follower and a horizontal portion extending rearwardly therefrom, and a unitary device for locking said follower in position within the compartment comprising a transverse portion having cam members at opposite ends thereof, said cam members being egg-shaped, disposed with the widest portion thereof down, and adapted to be rocked about their widest portions into locking engagement with said inwardly extending flanges.

7. A follower assembly for a filing compartment having a bottom wall and oppositely disposed side walls having inwardly extending flanges disposed above the level of the bottom

wall, said assembly comprising a follower having an upwardly extending portion adapted to support material within the compartment in front of the follower and a base extending rearwardly therefrom and adapted to lie along the upper surface of said bottom wall, and a unitary device for locking said follower in position within the compartment comprising a transverse connecting portion having elongated cam members at opposite ends thereof, said cam members being adapted to be rocked into locking engagement with said inwardly extending flanges and said base, the portions of said cam members engaging said flanges being laterally offset from and spaced farther apart than the portions of said cam members engaging said base.

8. A locking device for a filing compartment follower comprising a transverse member having elongated cam members at the ends thereof, said cam members being of greater length than the depth of the transverse member, being disposed substantially at right angles to the transverse member, and having rounded upper portions of relatively short radius of curvature and rounded lower portions of relatively long radius of curvature whereby said cam members may be rocked into locking engagement between a portion of a filing compartment and a portion of a follower therein.

9. A locking device for a filing compartment follower comprising a transverse member having elongated cam members at the ends thereof, said cam members being disposed substantially at right angles to the transverse member, having rounded upper portions of relatively short radius of curvature whereby said cams come into locking engagement with a portion of a filing compartment, and having rounded lower portions of relatively long radius of curvature which are offset inwardly from the upper portions thereof.
